T. J. BLOSICK

WIRE STRETCHER

Filed July 28, 1925

UNITED STATES PATENT OFFICE.

THOMAS J. BLOSICK, OF PORTLAND, OREGON.

WIRE STRETCHER.

Application filed July 28, 1925. Serial No. 46,620.

To all whom it may concern:

Be it known that I, THOMAS J. BLOSICK, a citizen of the United States, residing at Portland, in the county of Multnomah, 5 State of Oregon, have invented certain new and useful Improvements in Wire Stretchers; and I do hereby declare the following to be a full, clear, and exact description of the invention, such as will enable others 10 skilled in the art to which it appertains to make and use the same.

This invention relates to new and useful improvements in wire stretchers.

One object of the invention is to provide a device of this character which is simple in construction, and which is durable 15 and effective in operation.

Another object is to provide a device of this character wherein the stretching mechanism is adapted to be adjusted vertically 20 in accordance with the height of the wire to be stretched.

Another object is to provide a novel 25 ratchet mechanism for preventing retrograde movement of the winding mechanism.

Other objects and advantages will be apparent from the following description when taken in connection with the accompanying drawing.

30 In the drawing:

Figure 1 is a side elevation of the wire stretcher in operative position.

Figure 2 is a top plan view of the same.

Figure 3 is a horizontal transverse section on the line 3—3 of Figure 1, showing 35 the ratchet mechanism, and passing through one of the openings of the driving gears.

Referring particularly to the accompanying drawing, 10 represents an upright which 40 is adapted to be driven into the ground adjacent a fence post, and in line with the wire to be stretched. A collar is disposed on the upright, as shown at 11, and is held in different adjusted positions by the screw 45 12.

In the upper end of the upright is formed an opening which receives an end 50 of the brace 13, the other end of said brace being formed with a chisel or pointed end adapted to be driven into the fence post 14, whereby to hold the upright 10 against 55 movement toward the post, under the resisting or pulling influence of the wire being stretched. Slidable on the upright are the integral ring portions 15, of the yoke 16, such ring portions resting on the adjustable collar 11, whereby to be supported

at the desired height. Disposed transversely through the outer end portions of the arms of the yoke 16 is a winding drum 17, on which the wire to be stretched is wound, 60 and on one end of this drum, externally of one of the said arms, is a large gear 18. Extending transversely through the yoke, adjacent the ring portions 15, is a second shaft 19, and on said shaft, outwardly of 65 the said arm of the yoke, is a smaller gear 20, which meshes with the gear 18. Also carried by the shaft 19, is a disk 21, which is set in a circular recess 22, formed in the outer face of said arm of the yoke. In this 70 disk are formed the openings 23, each of which is adapted to register with an opening 24, in the said yoke arm, shown in the sectional view Figure 3. In the other arm of the yoke, in alignment with the opening 24, is an opening 25, and disposed in said openings is a bar 26, one end of which is disposed through the opening 24 for engagement successively in the openings 23, 75 of the disk, while the other end extends 80 beyond the side of the yoke and is threaded to receive the nut 27, and washer 28. The intermediate portion of the bar 26 is formed with a shoulder 29, and encircling 85 the bar, between the shoulder and the last-named arm of the yoke, is a coil spring 30, which urges the bar toward the openings of the disk. Upon turning the nut in one direction, the bar will be withdrawn from 90 engagement with the openings of the disk, while upon turning the nut in the opposite direction, the spring 30 is permitted to act upon the bar to urge the same toward the disk, for engagement in the openings thereof. The face of the disk 21, which bears 95 against the bottom of the recess 22, has a series of inclined grooves 31, each of which passes into an opening 23, for guiding the adjacent end of the bar 26 out of the openings. The said adjacent end of the bar 26 100 is preferably beveled, to a slight degree, whereby to engage against the wall of an opening 23, opposite to the groove 31, thereof, to maintain the disk, and the gear 20 against retrograde rotation. The shaft 19 105 projects beyond the gear 20, and has a crank handle 32 removably secured thereto, for rotating said shaft and gear.

The end of the brace 13, which extends 110 through the upper end of the upright 10, is provided with an opening 33, for the reception of an end of a guy wire 34, the other

end of which is secured to a stake, not shown. In the operation of the device, the upright 10 is driven into the ground at the proper distance from the fence post, and in the line 5 of the fence, with the brace 13 in the opening in the upper end of the upright, and with its other end driven into the post. The guy 34 may be used or not, as desired. The wire to be stretched, or the wire which is 10 connected with the woven wire section 36, is passed through an opening in the winding drum 17, and properly secured against withdrawal. The operator then grasps the 15 crank and rotates the same whereby to cause the drum to wind the wire onto the drum. As the gears rotate the disk will also rotate to successively bring its openings 23 in 20 position to receive the adjacent end of the bar 26, which bar end snaps into the opening, and then rides out of the opening on the inclined bottom wall of the groove of the opening, ready to drop into the next opening. This continues as long as the gear and disk are rotated. The tension of the wire 25 being stretched will tend to cause the gears to rotate in a retrograde direction, but will be prevented from such movement by the engagement of the bar against the deeper wall of the opening 23. The bar thus 30 performs the function of a pawl, while the openings 23, and inclined grooves perform the function of ratchets, with the result that the drum can be rotated until the wire is

properly stretched, without danger of the drum permitting unwinding of the wire. 35 After the wire has been stretched, the device is removed and set up at the next post of the fence, and the foregoing operation repeated.

What is claimed is:

1. A stretching device including a support, a yoke supported on the support, a winding drum on the support, gears for rotating the drum and including a disk having openings, a spring pressed bar having an end arranged to successively enter said openings as the disk is rotated, means for urging the bar into the openings, and means for withdrawing and retaining the bar out of engagement with said openings. 40

2. A stretching device including a support, a yoke on the support, means on the support for holding the yoke at different heights thereon, a winding drum in the yoke, gears for rotating the drum and including a disk having a circular series of openings, one face of the disk having an inclined groove extending into each opening, and a spring pressed bar carried by the yoke having an end arranged to snap into the openings successively and to ride thereout through said grooves. 55

In testimony whereof, I affix my signature.

THOMAS J. BLOSICK.
